UNITED STATES PATENT OFFICE.

JAKOB SULZER, OF WINTERTHUR, SWITZERLAND, ASSIGNOR TO GEBRÜDER SULZER, OF WINTERTHUR, SWITZERLAND, A FIRM.

INTERNAL-COMBUSTION ENGINE.

No. 886,662.

Specification of Letters Patent.

Patented May 5, 1908.

Application filed July 27, 1905. Serial No. 271,544.

To all whom it may concern:

Be it known that I, JAKOB SULZER, a citizen of the Republic of Switzerland, and a resident of Winterthur, Canton of Zurich, 5 Republic of Switzerland, have invented certain new and useful Improvements in Internal-Combustion Engines, of which the following is a specification.

My invention relates to so-called slow-burning internal combustion engines wherein the duration of the period of burning of the fuel in the production of the pressure medium is regulated by the rate of introduction of the fuel.

As is well known, internal combustion engines as heretofore operated on the slow burning principle, have had the air separately compressed and the fuel gradually introduced into the compressed air accompanied by simultaneous ignition and burning. It has also been proposed in operating internal combustion engines heretofore, to over-compress a portion of the explosive mixture or of the fuel up to or beyond a temperature that will cause ignition, in order to avoid the use of external or auxiliary sparking or igniting attachments.

According to the present invention, air is used as the igniting medium, either in its pure state or with a dilution of fuel or of some inert gas and this air, after being compressed in the main compression chamber of the engine, by the instroke of the working piston, has a portion over-compressed in a small supplemental pressure chamber having an independent piston, or other means for compression and delivery and communicating with the working cylinder through restricted passages, in such a manner that 40 when the over-compression has taken place up to a temperature sufficient to ignite fuel this superheated air is forced through the restricted passages in the working cylinder, and the fuel which it is desired to so ignite, 45 and to burn to produce the actuating pressure of the engine, is sprayed or otherwise introduced into the body of compressed air in the combustion chamber of the working cylinder or on its way thereto and in contact 50 with the jet of superheated air. By this means, the rate of burning may be regulated not only by the character of the superheated air introduced, but also by the character of the over-compression and delivery and the 55 pressure developed may also be made to cor-

respond to any curve by the rate at which the fuel is introduced.

The invention is illustrated in the accompanying drawings in which two embodiments are shown by way of explanation 60 Figures 1 and 2 being axial sections of an engine constructed and operating in accordance with my invention and Fig. 3 a modification of the gearing, Fig. 4 is a section through the engine showing the inlet valves 65 for the air to the main cylinder.

Similar letters refer to similar parts throughout the figures.

a is the working cylinder in which operates the piston *k* having piston rod *e*; *b* is a 70 smaller supplemental cylinder arranged at the end of or laterally to the working cylinder and having its interior in open communication with the compression chamber of the working cylinder through the medium of one 75 or more restricted passages *o* which preferably are of inwardly tapering form; the cylinder *b* is provided with a piston *c* which is operated by any suitable exterior mechanism such as *s*.

The operation of the engine is as follows: During the outward stroke of the piston *k*, air is introduced from the outer atmosphere into the compression chamber through the inlet-valves *Z* in the customary manner. 85 When the piston moves inwardly, the air is compressed not only in the working cylinder but also in the chamber *b* into which the air passes through the passages *o*. In the neighborhood of the inner dead point of the 90 piston *k* a sudden and rapid inward movement or compression stroke is imparted to the piston *c*, through the medium of its controlling mechanism, which movement is entirely independent of the movement of the 95 piston *k*. As the air in the cylinder *b* cannot escape rapidly enough through the narrow passages *o*, (Fig. 1) the air is over-compressed and its temperature raised to such an extent that it is capable of igniting fuel with 100 which it comes into contact. During the succeeding part of the movement of the piston *k*, the supplemental piston *c* forces the highly superheated air gradually through the 105 passages *o* back into the working cylinder. On the way (in the present instance in the pressure chamber of the working cylinder) the air jet has injected into it, a suitable fuel which is introduced through the channel *f* and the ring shaped pipe *m* which latter is 110

provided with a number of openings and arranged in the working cylinder *a*. The fuel is ignited by the superheated air and burns. This burning is more or less gradual according to the character or duration of this air introduction and consequently according to the nature and speed of the stroke of the piston *c*.

The controlling of the piston *c* may be effected by any suitable known means, such as by cams or eccentrics or the like; or it may be effected by electric, hydraulic, or pneumatic action.

In the embodiment shown in Fig. 1 the controlling of the piston *c* is effected by pneumatic action. A piston *t* working in an auxiliary cylinder *h*, has its piston rod *g* connected to the lever *s*. The cylinder *h* communicates with the compression chamber of the working cylinder through the medium of a pipe *i*, in which is arranged a valve *p*. On the crank shaft *n* is arranged a cam *q* which engages a roller *u* on a rod *r* connected to the valve *p*. A spring *v* tends to keep the roller *u* in engagement with the cam *q*. During the rotation of the driving shaft *n* and when the piston *k* is near its upper dead point, the cam *q* lowers the rod *r* which opens the valve *p* to admit pressure medium from the compression chamber into the auxiliary cylinder *h*. The pressure in the cylinder *h* forces the piston *t* outwardly and through the medium of the lever *s* the piston *c* is forced inwardly. By suitably controlling the opening and closing of the valve *p* the movement of the piston *t* may first be caused to take place with a sudden start and then continue at less speed.

Instead of the fuel passing through a number of holes it may be introduced through an annular slit *m* as shown in Fig. 2.

The devices shown in Figs. 2 and 3 are modifications of means for actuating piston *c*. In Fig. 2 the cam *q* is mounted on the crank shaft *n* while in Fig. 3 a shaft *y* is provided which enables the cam to operate directly on the roller *x* of lever *s*.

The manner in which the combustion proceeds, depends upon the manner of fuel introduction and upon the nature of the movement of the piston *c*; that is to say it depends upon the independent exterior controlling mechanism. It is therefore, possible to obtain either slow or rapid, and either continuous or intermittent combustion at will, as any suitable kind of controlling mechanism may be used for the purpose of injecting the fuel, and for forcing in the igniting air.

The functions of the supplemental cylinder *b* in connection with the supplemental piston *c*, and the fuel supply are such that not only is any kind of igniter unnecessary

but also any kind of gasifier, vaporizer or atomizer. The supplemental cylinder may also be used as a starting device in which case the working cylinder is filled with compressed air by hand or by means of pumps or from reservoirs, and the first combustion is thereupon effected by sudden downward movement of the piston *c*, after which normal working of the engine takes place.

It is not indispensable that the supplemental cylinder *b* contain pure air; on the contrary, a pipe *l* having a suitable cut-off member *l'* may be provided through which fuel in the form of gases, vapors, dust or liquid may be introduced into the cylinder *b*. This arrangement is preferably used when the fuel introduced through the pipe or slit *m* is difficult to ignite, or when it is desired to obtain the igniting temperature in the cylinder *b* with a slighter amount of compression, or when two different kinds of fuel are to be used, such as liquid fuel and coal dust.

The passages *o* (Fig. 1) may open into the working cylinder at any suitable place and may extend in any suitable direction and they may be provided with suitable nozzles in order to extend the combustion in the working cylinder.

The chamber *b* may even contain absolutely neutral gases, when the desired object is simply to generate, by the first rapid downward movement of the piston *c*, a temperature that is sufficient to effect during the following gradual forcing of the gases into the working cylinder first an ignition and then a gradual burning in the said working cylinder. Also in the cylinder *a* the air may be mixed with neutral gases such as residues from combustions, or certain fuels, such as very poor gases, if it be desired to modify the rate of burning by so doing.

Having thus described my invention, what I claim and desire to secure by Letters Patent is:

In an internal combustion engine, the combination with the working cylinder and its piston compressing air therein, of a supplemental cylinder directly communicating with the working cylinder through a restricted passage, means constructed to first suddenly compress an igniting medium in the supplemental cylinder and then force it gradually into the working cylinder, and separate means for feeding fuel to the igniting medium as it enters the working cylinder.

The foregoing specification signed at Winterthur this 30th day of June, 1905.

JAKOB SULZER.

In presence of—

AUGUST MÄRKLIN,
VALENTIN HOUGHER.
